(57) **CLAIM**

The ornamental design for an automatic vending machine, as shown and described.

DESCRIPTION

The patent or application file contains at least one drawing executed in color. Copies of this patent or patent application publication with color drawing(s) will be provided by the Office upon request and payment of the necessary fee.

1. Automatic vending machine

1.1 : Perspective

1.2 : Front

1.3 : Back

1.4 : Right

1.5 : Left

1.6 : Top

1.7 : Bottom

In reproductions 1.1, 1.2, and 1.6, the areas colored in yellow show portions of the article that form no part of the claimed design. The portions of the article shown in broken lines in reproductions 1.1-1.5 and 1.7 form no part of the claimed design.

1 Claim, 6 Drawing Sheets
(3 of 6 Drawing Sheet(s) Filed in Color)
